(57) **CLAIM**

The ornamental design for a computer chassis, as shown and described.

DESCRIPTION

FIG. 1 is a perspective view of a computer chassis according to a first embodiment of the present design;

FIG. 2 is a left-side elevation view thereof;

FIG. 3 is a right-side elevation view thereof;

FIG. 4 is a rear elevation view thereof;

FIG. 5 is a front elevation view thereof;

FIG. 6 is a top plan view thereof;

FIG. 7 is a perspective view of a portion of a computer chassis according to a second embodiment of the present design; and,

FIG. 8 is a front elevation view of the computer chassis of FIG. 7, those features not shown in the views of FIGS. 7 and 8 are disclaimed as forming no part of the claimed design. The ornamental design which is claimed is shown in solid lines in the drawings.

The bottom of the computer chassis is non-ornamental and forms no part of the claimed design. The broken lines, showing a display panel in FIGS. 1–6, represent unclaimed environment. All remaining broken lines illustrate portions of the computer chassis that form no part of the claimed design.
